CLAIM

The ornamental design for a monitor stand, as shown and described.

DESCRIPTION

FIG. 1 is a perspective view of a monitor stand in a first position of use showing my new design;

FIG. 2 is a perspective view of the monitor stand in a second position of use;

FIG. 3 is another perspective view of the monitor stand in a third position of use;

FIG. 4 is a front elevational view of the monitor stand in the first position of uses;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines in the drawings depict portions of the monitor stand that form no part of the claimed design.
